UNITED STATES PATENT OFFICE.

CHARLES E. FANNING, OF DAVENPORT, IOWA, ASSIGNOR OF ONE-THIRD TO HENRY C. FIRST, ANDREW OLSEN, GUSTAVUS SHALLBERG, AND WILLIAM A. MEESE, ALL OF MOLINE, ILLINOIS.

VENDING-MACHINE.

1,149,997.

Specification of Letters Patent.

Patented Aug. 10, 1915.

Application filed May 4, 1914. Serial No. 836,204.

To all whom it may concern:

Be it known that I, CHARLES E. FANNING, of Davenport, in the county of Scott and State of Iowa, have invented certain new and useful Improvements in Vending-Machines; and I do hereby declare the following to be a full, clear, and exact description of the invention, such as will enable others skilled in the art to which it appertains to 10 make and use the same.

This invention relates to that class of vending machines employed in connection with the sale of insurance stamps which are usually disposed of in blocks or rolls.

15 The primary object is to make the operation of the apparatus depend upon both the width and thickness of the article to be inserted therein, such as an envelop containing a single coin of a predetermined denomination.

20 In the accompanying drawings, Figure 1 is a front elevation with a portion of the inclosing casing removed. Fig. 2 is a side view showing the locking members in their unlocked positions in full lines and in their locking positions in dotted lines. Fig. 3 is a view showing the parts in their opened positions. Fig. 4 is a section on line 4—4 Fig. 2 showing the front locking member in 30 its locking position. Fig. 5 is a fragmentary sectional view showing the locking members in their locking positions.

Referring to the drawings, 1 designates a reservoir which is shown as of cylindrical 35 formation and designed to accommodate a series of rolls 2 which in the present instance may be regarded as rolls of insurance stamps, but the invention may be employed in vending articles of various kinds. The 40 reservoir 1 normally occupies an upright position, being supported by a frame 3 within an inclosing casing 4 which latter has a discharge outlet 5 at its front through which the articles may be delivered to the pur- 45 chaser.

6 designates a delivery platform which is provided with opposite parallel arms 7 which are journaled at their rear ends on a shaft 8 supported by frame members. This 50 platform at its front end carries a block or thickened portion 10 which normally fits in and closes the lower end of the reservoir, but when the platform is tilted the lower-most article will pass from the reservoir

with the platform, and as the latter is moved 55 downwardly a sufficient distance such article will be discharged from the machine.

Immediately beneath the platform is a guide which normally occupies a position parallel with the underside of the platform, 60 but may be moved relatively thereto a short distance, when the platform is in its normal position. This guide is shown in the form of a frame 12 having two parallel arms and an intermediate connecting piece 13, and 65 said arms at their rear ends are fixedly secured to a sleeve 14 which is fixedly mounted on shaft 8. From the rear side of sleeve 14 extends a weighted arm 15 which serves to return the guide and the platform to their 70 normal positions, the return of the guide causing the return of the platform.

According to my invention a duplex lock is provided for retaining the guide and platform in their normal positions, the releasing 75 of such lock being dependent upon the insertion of an article of a predetermined width and thickness. In the present instance I have shown the lock as consisting of a front locking member 16 and two rear 80 locking members 17, both sets of locking members being loosely mounted on a cross-rod 18. The locking member 16 is shown in the form of a forwardly and downwardly curved arm which terminates in a hook 19 85 which is designed to enter a slot 20 in sleeve 14 which I have shown as extending longitudinally of the latter, but it is manifest that instead of the slot 20 any surface on the sleeve with which the arm may engage will 90 answer equally as well. This arm is shown as carrying a roller 21 which extends into the pathway formed by the space between the platform and the guide, said roller being shown as mounted in a U-shape bracket 95 secured to the arm.

The locking members 17 are shown in the form of levers of the second order fulcrumed on cross-rod 18 and having their front arms downwardly and rearwardly 100 curved, said arms extending through the pathway formed by the platform and the guide and terminating at a point beneath the sleeve. These levers are located between the sides of the guide and platform. The 105 rear arms of the levers are weighted and terminate in hooks 22 which are designed to interlock with sleeve 14 at the rear thereof,

made within the scope of the claims hereto appended without departing from the spirit of my invention.

I claim as my invention:

- 5 1. In a vending apparatus, a rotatable shaft, locking mechanism therefor comprising two sets of locking means for engaging said shaft, one of which sets is designed to be moved into an unlocking position a predetermined distance in one direction while the other set is designed to be moved into an unlocking position a predetermined distance in a different direction to permit such shaft to be rotated.
- 10 2. In a vending apparatus, locking mechanism comprising a rotatable shaft, a locking member normally engaging said shaft and designed to be free therefrom when moved a predetermined distance in one direction by the article to be inserted in the apparatus, and locking members normally engaging said shaft and designed to be freed therefrom when moved a predetermined distance in a different direction by such article.
- 15 3. In a vending apparatus, locking mechanism comprising a rotatable shaft, a locking lever normally engaging said shaft at one end and extending at its other end into the path of the article to be inserted in the apparatus and arranged to be moved out of said path, and two spaced-apart independently operating locking levers parallel to each other and to the first mentioned lever, each of said spaced-apart levers normally engaging said shaft at one end and also ex-

tending at its other end into said path and arranged to be moved by the advance of the article inserted into the apparatus.

4. In a vending apparatus, a locking mechanism comprising a rotatable shaft 40 having a guide-frame forming a pathway for the article to be inserted in the apparatus, a locking member for normally engaging said shaft and extending into said pathway, two spaced-apart locking members normally 45 engaging said shaft and also extending into said pathway, and means for turning said shaft when released by said locking members.

5. The combination with a reservoir and a tilting platform therefor, of a rotatable shaft carried thereby and having a guide frame paralleling the underside of said platform and forming a pathway for the article to be inserted in the apparatus, locking 50 means engaging said shaft and extending into such pathway, means for rotating said shaft to lower said frame and platform, a stop for limiting the movement of said platform to allow said frame to move independently thereof, and means for returning said frame and platform to their normal positions.

In testimony whereof, I have signed this specification in the presence of two subscribing witnesses.

CHARLES E. FANNING.
